BOWLING BALL

Filed April 5, 1948

UNITED STATES PATENT OFFICE

2,539,918

BOWLING BALL

William McLaren, Kearny, N. J.

Application April 5, 1948, Serial No. 18,931

10 Claims. (Cl. 33—174)

1

My invention relates generally to bowling balls, and specifically to bowling balls having finger holes which may be spacially displaced in relation to each other, and having finger sockets which are replaceable by finger sockets of varying dimensions and position.

It is among the objects of my invention to provide a bowling ball which has finger holes that may be spacially displaced with relation to each other without varying the perfect sphericity of the bowling ball.

It is a further object of my invention to provide a bowling ball which has replaceable finger sockets which separately and in combination with the first mentioned object, will supply a ball variable in every characteristic except weight.

Still another object of my invention is to provide an adjustable bowling ball that may be used for trial and test purposes preliminary to ordering one permanently made.

And another object of my invention is to provide a bowling ball which is adjustable, and which may be calibrated so that a desired adjustment may be reset at any time by reference to the calibration, or a custom made permanent ball may be made merely by reference to the settings of the calibrations.

Another object of my invention is to provide a bowling ball that has a span adjustment feature, a bridge adjustment feature, and with which exchangeable finger hole bushings may be supplied, or the standard bored finger holes may be used.

It is a further object of my invention to provide a bowling ball which is simple and easily adjustable and variable over a wide range of finger hole spans.

Yet another object of my invention is to provide a bowling ball having hemispheric sections rotatable with respect to each other, one carrying a thumb hole, and the other carrying one or more finger holes, whereby the span distance may be increased or diminished in accordance with preference.

The accompanying drawings present embodiments of structure illustrating my invention as hereinafter detailed. They are intended as examples of the application of my invention, and not as limiting the invention, which invention includes all other forms which are within the scope of the hereinafter set forth claims.

In the drawings:

Figure 1 is an elevational view of my invention;

Figure 2 is a cross-section taken on the line 2—2 of Figure 1;

2

Figure 3 is a view in perspective of the finger hole bushings;

Figure 4 is an exploded view of the ball showing the cylindrical insert;

Figure 5 is a top view of the bottom hemisphere; and

Figure 6 is a partial side view of the bottom hemisphere.

Referring now to the drawings in detail, my invention provides a bowling ball 11 composed of a top hemisphere 12 and a bottom hemisphere 13, which are complementary. The top hemisphere 12 has a cylindrical insert 14 with an end 15 whose curvature conforms to the surface curvature of the ball 11. The insert 14 rests in a cylindrical passage 16. The passage 16 has a partially threaded passage 17 extending perpendicular thereto. A spring 18 is located in this passage in engagement with a pin 19. A threaded retainer 20 engages a flange 21 on the pin 19 and serves to keep it protruding no more than a brief interval into the passage 16. Here it engages an annular groove 22 on the insert 14, whereby the insert is retained in but readily removable from the passage 16, but is, nevertheless, freely rotatable. The insert 14 has its end 15 supplied with a reference point 23. Around the edge of the passage 16, an angular deviation scale 24 is marked to cooperate with the reference point 23. The equatorial edge of the top hemisphere 12 is marked with a scale 25, preferably in inches, and the equatorial edge of the bottom hemisphere 13 is supplied with a reference point 26. The bottom hemisphere 13 has a radial passage 27 into which a thumbhole bushing 28 with a central passage 29 of selected diameter may be inserted. The hemispheres 12, 13 have a vertical shaft 30 into which a flanged nut 31 with a wrench socket 32 in the head, is in threaded engagement with a bolt 33. The hemispheres 12, 13 are thereby held together.

The top hemisphere 12, at the end of the vertical shaft 30, has an annular cut-out portion 34, in which a hollow cylindrical member 35 is positively affixed. This member 35 has a worm wheel 36 at one end. A rod 37 passes through the bottom hemisphere 13 in a channel 38 and terminates in a worm 39 which is engaged with the worm wheel 36. This rod is provided with a wrench socket 40 whereby the hemispheres 12, 13 are rotated with respect to each other. By tightening the nut 31, the hemispheres 12, 13 may be locked against any further rotation.

The insert 14 is provided with two equal cylindrical passages 41, 42. A pair of cylindrical

bushings 43, 44 are inserted in the passages 41, 42. The bushings are frictionally positioned and have finger holes 45, 46 for the first and second fingers. These finger holes are off-center with a diameter suitable to the appropriate fingers. Being off-center holes, they are disposed not less than three-sixteenths of an inch from the outer wall of their respective bushings, whereby a minimum bridge indicated by the bracket 47 will be no less than three-eighths of an inch to conform to accepted standards. When the bushings 43 and 44 are rotated in the insert 14, the size of the bridge 47 may be varied to suit. Further, bushings 28, 43, 44 with different size finger holes may be provided to suit the needs of any bowler.

My bowling ball is intended primarily as an aid to the proper fitting of a permanent, non-adjustable bowling ball. For that purpose it may be used as follows. A wrench is applied to the socket 32 to loosen the nut 31. This permits rotation of the hemispheres 12, 13 with respect to each other. A wrench applied to the socket 40 rotates the hemispheres 12, 13 decreasing or increasing the span distance between the thumbhole bushing 28 and the finger hole bushings 43, 44. When the desired span distance is achieved; the deviation from zero may be read on the scale 25. The normal adjustment of the fingers will also cause the insert 14 to revolve, and the deviation of the insert from zero degrees may be read on the scale 24. With the two readings, it will be easy to make a permanent bowling ball with the preferred characteristics chosen by manipulation of the adjustable ball. By substituting bushings 28, 43, 44 with various thumb and finger hole diameters, holes of like size may be provided in the permanent ball, by reference to the characteristics marked on each of the selected bushings.

It will be seen that the use of my ball permits of almost unlimited variations and experimentation as a prelude to the ordering of a custom made bowling ball and insures that the custom made ball will have the precise characteristics chosen by manipulation of the adjustable ball.

Inasmuch as many changes may be made in the selection, construction and arrangement of the component parts of my bowling ball, all within the scope of the appended claims, it is intended that such equivalents shall be considered as therein included.

I claim:

1. A bowling ball comprising complementary segments of a sphere, a means for rotatably connecting the segments together, a thumbhole in one segment, a rotatable insert in the other segment, a worm wheel connected to one segment, a means for rotating the worm wheel extending through the other segment, and one or more finger holes in the rotatable insert.

2. A bowling ball comprising complementary segments of a sphere, a means for rotatably connecting the segments together, a thumbhole in one segment, a rotatable insert in the other segment, one or more finger hole bushings in the rotatable insert, a worm wheel connected to one segment, and a means for rotating the worm wheel extending through the other segment.

3. A bowling ball comprising complementary segments of a sphere, a means for rotatably connecting the segments together and frictionally engaging them against movement with respect to each other, a thumbhole in one segment, a rotatable insert in the other segment, one or

more finger holes in the rotatable insert, a worm wheel connected to one segment, and a means for rotating the worm wheel extending through the other segment.

5. A bowling ball comprising complementary segments of a sphere, a means for rotatably connecting the segments together, a calibrated scale on the edge of one segment, a reference point on the corresponding edge of the other segment, a thumbhole in one segment, a rotatable insert in the other segment, a worm wheel connected to one segment, a means for rotating the worm wheel extending through the other segment, and one or more finger holes in the rotatable insert.

10 15 10. A bowling ball comprising complementary segments of a sphere, a means for rotatably connecting the segments together, a thumbhole in one segment, a rotatable insert in the other segment, a calibrated scale and a reference point on the insert and its segment, a worm wheel connected to one segment, a means for rotating the worm wheel extending through the other segment, and one or more finger holes in the rotatable insert.

20 25 15. A bowling ball comprising complementary segments of a sphere, a means for rotatably connecting the segments together, a thumbhole in one segment, a rotatable insert in the other segment, a calibrated scale and a reference point on the insert and its segment, a worm wheel connected to one segment, a means for rotating the worm wheel extending through the other segment, and one or more finger holes in the rotatable insert.

25 30 20. A bowling ball comprising complementary segments of a sphere, a means for rotatably connecting the segments together, a thumbhole in one segment, a rotatable insert in the other segment, a calibrated scale and a reference point on the insert and its segment, a worm wheel connected to one segment, a means for rotating the worm wheel extending through the other segment, and one or more finger holes in the rotatable insert.

35 40 30. A bowling ball comprising complementary segments of a sphere, a means for rotatably connecting the segments together, a worm wheel connected to one segment, a worm in operable engagement with the worm wheel and extending through the other segment, a thumbhole in one segment, and one or more finger holes in the other segment.

45 50 35. A bowling ball comprising complementary segments of a sphere, a calibrated scale on the edge of one segment, a reference point on the edge of the other segment, a means for rotatably connecting the segments together and frictionally engaging them against movement with respect to each other, a worm wheel connected to one segment, a worm in operable engagement with the worm wheel and extending through the other segment, a thumbhole in one segment, a rotatable insert in the other segment, a calibrated scale and a reference point on the insert and its segment, a means for retaining the insert in its segment, and one or more finger holes in the rotatable insert.

55 60 40. A bowling ball comprising complementary segments of a sphere, a means for rotatably connecting the segments together, a thumbhole in one segment, one or more finger holes in the other segment, a gear connected with one segment, a means for rotating the gear and in operable engagement therewith extending through the other segment whereby the segments are rotated with respect to each other.

65 70 45. A bowling ball comprising complementary segments of a sphere, an axial passage extending through the segments, enlargements of the axial passage at the outer ends thereof, axial members disposed in the passage with their inner ends in threaded engagement, an enlarged portion at the end of each axial member positioned in the enlargements of the axial passage, a surface on the enlarged portion of an axial member adapted to be engaged with a means

for rotating the axial member and adjusting the threaded engagement of the ends of the axial member whereby the segments may be frictionally engaged against movement with respect to each other, a worm wheel connected to one segment, a worm in operable engagement with the worm wheel and extending through the other segment, a hole in one segment, a rotatable insert in the other segment, a means for retaining the rotatable insert in its segment, and 10 a hole in the insert.
